UNITED STATES PATENT OFFICE.

WILLIAM C. CODMAN, OF PROVIDENCE, RHODE ISLAND, ASSIGNOR TO THE GORHAM MANUFACTURING COMPANY, OF SAME PLACE.

DESIGN FOR A HANDLE FOR SPOONS, &c.

SPECIFICATION forming part of Design No. 31,998, dated December 19, 1899.

Application filed November 22, 1899. Serial No. 737,958. Term of patent 7 years.

To all whom it may concern:

Be it known that I, WILLIAM C. CODMAN, a subject of the Queen of Great Britain, residing at Providence, in the county of Providence and State of Rhode Island, have invented and produced a new and original Design for the Handle of a Spoon, Fork, or Similar Article, of which the following is a specification, reference being had to the accompanying drawings, forming part thereof.

In the drawings, Figure 1 is a view of the front of my newly-designed handle, shown in connection with the bowl of a spoon, the blade and tines of a fork being indicated in broken lines. Fig. 2 is an enlarged sectional view of the front surface of the handle on the line X-X in Fig. 1.

The leading feature of my design consists in the convex central panel inclosed within three marginal beads, the central large and bold bead having on its inner side a smaller bead, extending around the central panel, and on its outer side a bead of smaller cross-section, extending in unbroken continuity around the margin of the handle, the honeysuckle, central and scrolled-leaf ornament on the upper end of the handle overlying the large marginal bead and part of the smaller inner bead.

In the drawings, A indicates the bowl, B the shank, and C the blade, of the handle. The convex panel 1 conforms in its outline to

the general outline of the handle—broad at the blade of the handle and contracting to a mere line at the narrowest part of the shank. The bead 2 is of bold nearly semicircular cross-section. The narrower beads 3 and 4 are of slightly-flattened convex cross-section. The bead 3 extends along the whole margin of the handle, the bead 4 extending along the whole margin of the central convex panel 1, overlaid only in part by the ends of the foliated scrolls 5 and the scroll of the honeysuckle ornament 6 at the upper end of the handle. At the lower end of the handle the marginal beads terminate in the inwardly-curved foliated scrolls 7, surmounted by the pyramidal leaf-ornament 8, overlaying a portion of the central convex panel 1.

Having thus described my invention, what I claim as new, and desire to secure by Letters Patent, is—

The design for the handle of a spoon, fork or similar article substantially as herein shown and described.

In testimony whereof I have signed my name to this specification in the presence of two subscribing witnesses.

WILLIAM C. CODMAN.
